UNITED STATES PATENT OFFICE.

WILLIAM C. NORMAN, OF SMITHTON, ARKANSAS.

CALENDAR.

SPECIFICATION forming part of Letters Patent No. 709,353, dated September 16, 1902.

Application filed February 26, 1902. Serial No. 95,754. (No model.)

To all whom it may concern:

Be it known that I, WILLIAM C. NORMAN, a citizen of the United States, residing at Smithton, in the county of Clark and State of Arkansas, have invented certain new and useful Improvements in Perpetual Calendars, of which the following is a specification.

My invention is a calendar; and it consists of three disks—one outside disk, one central disk, and one intermediate disk—arranged with letters and numerals, so as to give perpetually the days of the week and month.

In the accompanying drawings, Figure 1 is a face view of my invention. Fig. 2 is a cross-sectional view of Fig. 1 on the line X X. Fig. 3 is a detailed view showing the construction of the nut and the manner in which the bolt is kept from coming out of the nut. Fig. 4 is substantially a repetition of Fig. 3, the bolt being elevated above the female thread of the nut. Fig. 5 represents another means of uniting the three disks, in which case the nut is a mere extension from the back wall of the outside disk.

It is primarily intended that this calendar be manufactured of aluminium and be about the size of a silver dollar; but it may be manufactured of any suitable material and may be any size.

My invention is described as follows:

1 represents the rim of the outside disk; 2, the rim of the intermediate disk, and 3 the central disk. The outside disk has its center cut away, forming a circular depression 4, however leaving a back 5. The intermediate disk fits in the depression 4 of the outer disk and has in its center a double recess 6 and 6', leaving a thin back 7. The central disk 3 fits in the recess 6' and has a thin flange 8, that fits in the recess 6. Each one of these disks has a concentric opening 9. (See Fig. 1.)

On the outer rim 1 and front face of the outside disk are abbreviated names 10 of the days of the week, and on the outer rim 2 and front face of the intermediate disk are the abbreviated names 11 of the months of the year.

The face of the central disk is divided into seven radial spaces, and these radial spaces are filled each with a line of figures 12, running radially from its center to its circumfer-

ence. (See Fig. 2.) The letters and figures may be raised by being stamped up on the faces of these disks or they may be applied to the same in any other way, provided they may be plainly and easily read.

The back side of the calendar is perfectly level and smooth and is used for advertising purposes.

The three disks are held together by a nut 13, passing through the center of them. The nut 13 has its lower end countersunk in the back 5 of the outside disk, and the front face of the center disk 3 has a depression in which is countersunk the upper end of a threaded bolt 14. The nut 13 has a female thread 15, and at the bottom of this female thread a smooth enlargement 16, the lower wall 17 of which is convex.

The bolt 14 is made of malleable material and has extending from its lower end two points 18. The said bolt 14 is screwed down into the female thread 15 of the nut 13, and when the points 18 strike the convex wall 17 they are bent out, and thus the bolt 14 cannot come out unless considerable pressure is brought to bear to unscrew it. The purpose of this arrangement is to keep the bolt 14 from coming out, and thereby keep the three sections of the calendar from coming apart.

When I wish to set the calendar, I insert a knife-blade or a screw-driver into the slit 19 of the bolt 14, and give it a half-turn. This loosens the bolt so that I can set the calendar, and when set I turn the bolt in again until it is tight. However, for cheaper calendars I can unite the three parts by a simple nut countersunk at both ends, or I may make the outside disk with a central elevation 20, which will answer for a nut, and instead of having it centrally threaded I may Brad the upper end of it down, and thus hold the three parts of the calendar together.

To operate the calendar, (we will begin on the first day of January, for the year 1902, to illustrate) turn the calendar until "Sunday" is up, and as January, 1902, begins on Wednesday, we will turn the second disk until "January" is opposite "Wednesday," and as January comes on Wednesday, we will read the days of the month beginning at the numeral "1," and reading to the right—for instance, "1" represents Wednesday,

January, the first; "2," the second; "3," the third; "4," the fourth; "5," the fifth; "6," the sixth; "7," the seventh, and then we read up to "8," which is Wednesday, January the eighth, and so on around until the month is completed; and then, as February begins on Saturday, we turn the second disk until "February" is under "Saturday," and then we turn the center disk until "1" is 10 under "February," and then, beginning at "1," we read: Saturday, February, the first; Sunday, the second; Monday, the third; Tuesday, the fourth; Wednesday, the fifth; Thursday, the sixth; Friday, the seventh, 15 and Saturday, the eighth, and so on around until the month is completed, and we complete this operation every month perpetually.

Having described my invention, what I 20 claim as new, and desire to secure by Letters Patent, is—

1. A perpetual calendar, consisting of three disks, the outside disk having a central depression, leaving an outer rim, and on said 25 outer rim the days of the week indicated equal distances apart; in said central depression journaled a second disk, having a double depression, leaving an outer rim 2, and on this outer rim the names of the months of 30 the year, and in the double depression of the second disk journaled a third disk, having a flange that works in the first step of the double depression just mentioned; said disk having radial lines extending from its center, 35 leaving between them equal spaces, and in these spaces, numerals so arranged that by turning the second and third disks, the days of the week and the month may be read perpetually; said disks each having in its center

a perforation and journaled together by a 40 nut passing through said central perforations, substantially as shown and described and for the purposes set forth.

2. A perpetual calendar, consisting of three disks, the outside disk having a central depression, leaving an outer rim, and on said outer rim the days of the week indicated equal distances apart; in said central depression journaled a second disk, having a double depression, leaving an outer rim 2, and on this outer rim the names of the months of the year, and in the double depression of the second disk, journaled a third disk, having a flange that works in the first step of the double depression just mentioned; said disk 55 having radial lines extending from its center, leaving between them equal spaces, and in these spaces, numerals so arranged that by turning the second and third disks, the days of the week and the month may be read perpetually; said disks each having in its center a perforation; a nut passing from the rear through said perforations, and having in its front end a female thread, and at the base of said female thread an enlargement, the 60 bottom wall of which is convex; a bolt having at its threaded end, two projections which pass into the said enlargement, and are bent out when said screw is turned home, substantially as shown and described and for 65 the purposes set forth.

In testimony whereof I affix my signature in presence of two witnesses.

WILLIAM C. NORMAN.
